(57) **CLAIM**

The ornamental design for a container assembly, as shown and described.

DESCRIPTION

FIG. 1 is a perspective view of the container assembly showing the new design;

FIG. 2 is a profile view of the container assembly of FIG. 1 as viewed in the direction of arrow A;

FIG. 3 is a profile view of the container assembly of FIG. 1 as viewed in the direction of arrow B;

FIG. 4 is a bottom view of the container assembly; and,

FIG. 5 is an enlarged perspective view of the band of the container assembly, shown separately for clarity of illustration.

The broken lines shown in the figures are for illustrative purposes only, and form no part of the claimed design.
